Primary Examiner — Brian N. Vinson(74) *Attorney, Agent, or Firm* — Hamre, Schumann, Mueller & Larson, P.C.(57) **CLAIM**

The ornamental design for a projector head yoke for ground-inserted lighting, as shown and described.

DESCRIPTION

FIG. 1 is a perspective view of projector head yoke for ground-inserted lighting showing our new design.

FIG. 2 is a perspective view thereof.

FIG. 3 is a right side view of FIG. 2 thereof.

FIG. 4 is a left side view of FIG. 2 thereof.

FIG. 5 is a front view of FIG. 2 thereof.

FIG. 6 is a rear view of FIG. 2 thereof.

FIG. 7 is a bottom view of FIG. 2 thereof; and,

FIG. 8 is a top view of FIG. 2 thereof.

The broken line disclosure represents portions of the projector head and stake which form no part of the claimed design.

1 Claim, 4 Drawing Sheets(56)
